UNITED STATES PATENT OFFICE

JAMES SLOCUM, OF DETROIT, MICHIGAN

SPARK ARRESTER

Application filed September 6, 1932. Serial No. 631,847.

My invention relates to a spark arrester to be installed on the top of a chimney or smoke stack,—which while not restricting the draft, is designed to prevent the escape of sparks or hot cinders that might alight upon combustible roofing, and thereby ignite the same and thus cause a very disastrous fire. It is well known that the annual fire loss resulting from sparks or burning embers falling from chimneys, is enormous and while this is particularly true of forced draft furnaces, it is also true of wood or coal burning stoves, and furnaces,—especially on farms where means for fighting fires is more or less limited.

It is well known that a creosote substance is constantly forming in stove pipes and chimneys, coating the walls of pipes and chimneys, until as a result of an unusually hot fire the creosote coating is ignited,—whereupon due to increased draft, hot embers and sparks are emitted through the chimney, falling therefrom upon the roof of the building and other adjacent structures, thus often resulting in a serious conflagration.

It is the object therefore of the present invention to construct a foraminous device which may be secured at the top of the chimney in any suitable manner, in which the draft openings are preferably of a lozenge or rhombic formation, the wall of the metallic fabric surrounding the openings being inclined inwardly in order that sparks striking the metallic frame bounding the lozenge-shaped openings, will be deflected inwardly, so that embers or sparks may drop downwardly within the chimney,—the draft however passing readily through the lozenge-shaped openings.

A further object of the invention is to provide a substantially arc-shaped hood constructed of similar foraminous material, which is secured to the end walls of the structure by spot-welding or other suitable means,—the side walls of the hood portion being inclined toward each other but spaced apart to provide a longitudinal central opening beneath the arc-shaped hood;—the walls being spaced at each side from the inclined side walls of the body portion to provide free lateral exits for draft.

A further object of the inclined side walls of the hood is to direct any sparks or relatively large embers that may rise above the inclined walls downwardly and inwardly into the chimney opening. 55

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same. 60

In the drawing accompanying this specification: 65

Figure 1 is a diagrammatical perspective view of the spark arrester, mounted upon the top of a chimney.

Figure 2 is a fragmentary cross-sectional view through the metal fabric, forming the spark arrester, showing the inclined marginal frame-work which bounds its lozenge-shaped openings. 70

Figure 3 is a fragmentary side elevation of the metal fabric, showing the skeletonized marginal inclined frame bounding its lozenge-shaped openings, the arrows indicating the manner in which said skeletonized inclined frame-work serves to deflect inwardly and downwardly sparks or embers contacting therewith. 75

Figure 4 is a vertical, diagrammatical, cross-sectional view of the structure shown in Figure 1, showing its overhanging cap or hood, with its inwardly and downwardly directed side walls, spaced from the inclined upwardly directed walls of the body of the structure;—the arrows indicating the manner in which sparks are deflected inwardly and downwardly by the inclined skeletonized frame of the structure bounding the lozenge-shaped openings. 85

Referring now to the letters of reference placed upon the drawing: 90

A denotes a chimney, B the spark arrester in its entirety, secured by suitable anchoring means C to the walls of the chimney.

The walls forming the foraminous structure are preferably bent to provide a plu- 100

rality of lozenge-shaped openings E, the walls D bounding said openings being inclined upwardly to direct the air passing laterally through the openings to increase the draft and inwardly to deflect sparks, cinders or the like downwardly and inwardly that they may not escape through the lozenge-shaped draft openings to cause roof or other fires,—the required draft not being impaired by the size or form of the egress openings of the structure.

While the structure may be of any suitable configuration, that shown in the drawing has been found desirable.

15 The side walls F, F of the device rise vertically for a suitable distance and are then inclined in a roof-like form F¹ inwardly and thence upwardly as denoted at F², providing a longitudinal central opening G extending 20 from end to end of the structure.

H, H are end walls which may extend slightly above the top of the side walls, through this is not material.

25 Covering the central opening G is a substantially arc-shaped cap or hood I, which viewed in cross-section, will be seen to have inwardly and downwardly inclined walls I¹,—spaced from the side walls F² of the body to provide an unobstructed opening J, at each 30 side of the structure. The inclined walls I¹ of the cap or hood, serve to direct any sparks or cinders coming in contact with the foraminated hood inwardly and downwardly into the chimney opening, thus preventing 35 their escape which otherwise might cause a conflagration.

Great care has been taken in designing the foraminous structure to provide for a maximum draft, while guarding the escape of 40 sparks, cinders or the like.

The device is simple and inexpensive in construction, and very efficient in the prevention of fires.

Having thus described my invention, what 45 I claim is:

1. A spark arrester adapted to be mounted over the egress opening of a chimney, consisting of a foraminous body of expanded sheet metal, forming inclined skeletonized 50 marginal frames bounding a plurality of lozenge-shaped openings the frame member bounding the upper portion of the lozenge-shaped opening being inclined, whereby sparks and cinders rising from the chimney 55 will be deflected by the inclined portions of said skeletonized frame inwardly, that they may drop downwardly into the chimney opening.

60 2. A spark arrester adapted to be mounted over a chimney opening consisting of a foraminous body formed of sheet metal comprising side and end walls, consisting of a skeletonized frame of expanded metal, bounding a plurality of draft openings, with 65 the upper part of each side wall inclined in-

wardly and thence upwardly in spaced relation to form a longitudinal opening extending centrally between the end walls of the structure; a foraminous hood member provided with downwardly and inwardly inclined side walls spaced from the upper margin of the side walls of the body structure to provide unobstructed lateral draft openings, whereby hot embers or sparks deflected by the top of the hood structure onto the side walls of the hood structure may be directed thence downwardly into the chimney opening.

3. A spark arrester adapted to be mounted over a chimney opening comprising vertical side and end walls, formed of expanded sheet metal bounding a plurality of draft openings, the upper longitudinal members of the frame, bounding said several draft openings being inclined, thereby increasing the draft resulting from the passage of air laterally and upwardly through the draft openings and whereby sparks and cinders rising from the chimney will be deflected inwardly and downwardly into the chimney opening; the upper portion of the opposing vertical side walls being inclined inwardly and thence upwardly in vertical parallel relation, said walls being spaced apart to form a longitudinal opening extending centrally between the end walls of the structure; and a foraminous hood member having downwardly and inwardly inclined side walls spaced from the upper margin of the vertical side walls of the body structure to provide unobstructed lateral draft openings through the side walls, whereby hot embers or sparks deflected by the top of the hood structure may be directed downwardly into the chimney opening.

In testimony whereof, I sign this specification.

JAMES SLOCUM.
